W. S. Granger.
Sp. St. Morris.
ATTORNEY.

UNITED STATES PATENT OFFICE.

WILLIAM S. GRANGER, OF DULUTH, MINNESOTA.

GAS-MIXER.

1,329,324.

Specification of Letters Patent.

Patented Jan. 27, 1920.

Application filed July 13, 1918. Serial No. 244,687.

To all whom it may concern:

Be it known that I, WILLIAM S. GRANGER, a citizen of the United States, residing at Duluth, in the county of St. Louis and State of Minnesota, have invented certain new and useful Improvements in Gas-Mixers for Engines, of which the following is a specification, reference being had therein to the accompanying drawing.

10 This invention relates to feed mixing devices for internal combustion engines and has special reference to a combined mixer and auxiliary air supply for the gas which forms the feed for such engines.

15 The principal objects sought are economy of fuel and improvement of the efficiency of the engine to which the device is applied.

Other objects are simplicity in construction, installation and operation.

20 Still other objects and advantages of the peculiar construction will appear in the further description of the invention.

In the accompanying drawings forming part of this application and in which like reference characters indicate like parts;

Figure 1 is a transverse sectional view through one of the devices showing the mixing wheel in elevation;

Fig. 2 is a similar view at right angles 30 to Fig. 1, also showing the mixing wheel in elevation, and

Fig. 3 is an elevation of the outer face of the removable portion of the wheel housing.

35 It is not considered necessary to illustrate the carbureter and cylinder of an internal combustion engine as their relation to each other is well understood by those skilled in the art and the different types

40 vary considerably in appearance, however, it is to be understood that this mixing device is to be installed within the gas feed supply conduit or pipe which leads from the carbureter to the engine. Such feed pipe is 45 clearly illustrated in Fig. 2 of the drawings, 1 being that portion of the pipe leading from the carbureter to the mixer and 2 that portion leading from the mixer to the engine.

3 represents the main body portion of the 50 mixer which is, in transverse elevation, the general form of flange connection employed between the feed intake manifold of the engine and the carbureter pipe, each of which is provided with an enlarged annular

flange 4 having a smooth or ground face 55 designed to abut each other either with or without a gasket and held tightly together by suitable through bolts in opposed holes formed within the flanges which properly register for such purpose when the ends of 60 the pipe are united.

The main body 3 of the mixer being of this same form and provided with opposed holes 5, is positioned intermediate of the ends of the portions 1 and 2 of the feed pipe 65 or conduit, and thus becomes a coöperative part thereof. The ends of the pipe and the mixer body are held together by the through bolts as above described.

The face of the body portion 3 of the 70 mixer toward the end 2 of the pipe, is bored out forming a chamber 6 concentric with the bore of the pipe though slightly smaller in diameter, and between the chamber and opposite outer face of the body 3 is left a 75 thin wall 7 in which is a series of radially positioned holes 8, preferably six in number.

In the circumferential wall of the chamber 6 is screw threaded a cylindrical housing 9 having a thin end wall 10 like the end 80 wall 7, and through which holes 11 similar to the holes 8 are formed.

When the housing is screw threaded within the body 3 and in operative position, it is preferred to have the holes 8 and 11 in 85 staggered relation to each other, that is, not opposite, the object of which is to create as tortuous a route as possible for the gas as it passes through the mixer.

Within the center of the wall 7 is a bearing 90 plug 12 which may or may not be made adjustable as desired, and in the center of the wall 10 is a similar plug 13 preferably made adjustable by being screw threaded within the wall 10 and having a jam nut 95 14 thereon, whereby the plug may be set at any desired adjustment. Intermediate of the concaved ends of the bearing plugs 12 and 13 is rotatably mounted the mixing fan wheel 15, the blades of which are set at an 100 angle similar to those of a boat propeller, whereby the passing of gas through the mixer causes the wheel to rotate rapidly.

A vertically disposed hole 16 is formed in one side wall of the body portion 3 and 105 communicates with the chamber 6 and the interior of the housing as at 17. This hole is for the purpose of admitting additional

air to the gas as it passes through the mixer, and, as it is thoroughly incorporated with the gas by the rotation of the wheel in the mixer, the principal objection to thus adding air to the gas just before entering the cylinder, is avoided, as it is well known that the addition of air in the ordinary manner is to a large extent impractical.

- I have illustrated a common spigot valve 10 at 18 controlled by a suitable lever 19 and rod 20 which may lead to any convenient place for manipulation by which the amount of air admitted to the mixer may be conveniently governed.
- 15 While I have shown the air supply as coming from no place in particular, except that it is outside of the conductor pipe or conduit, it is evident that in the event of the mixer being used in connection with a 20 water cooled engine, the air pipe may lead from the top of the radiator from whence air having more humidity therein than the ordinary atmosphere, may be had, but this I do not claim as new with me and forms 25 no part of the present invention.

From the foregoing it is apparent that I have devised means whereby air may be added to the mixture *en route* from the carbureter to the engine, and such additional 30 air not only thoroughly incorporated with the mixture, but the mixture itself consid-

erably improved by the motion of the mixing wheel.

Having thus described my invention, what I claim as new and desire to secure by Letters Patent, is—

A gas mixer for a separable gas conduit for engines comprising a single-piece principal body member held intermediate of the separable portions of the conduit and forming a co-operative part thereof and having a tangentially disposed port therein, communicating with the outside atmosphere, a central cylindrical screw-threaded chamber within the principal body portion communicating with the port and having a plurality of holes in one end thereof, and a second cylindrical chamber screw-threaded externally and engageable within the chamber in the principal body portion but not closing the port therein, said second chamber having one head formed integral therewith and having a plurality of holes therein and a mixing wheel supported by and intermediate of the heads.

In testimony whereof I hereunto affix my signature in the presence of two witnesses.

WILLIAM S. GRANGER.
